UNITED STATES PATENT OFFICE.

HAROLD H. BROWN, OF INDIANAPOLIS, INDIANA, ASSIGNOR TO UNIVERSITY OF CHICAGO, OF CHICAGO, ILLINOIS, A CORPORATION OF ILLINOIS.

DESIGN FOR A PLATE OR SIMILAR ARTICLE.

50,337.

Specification for Design.

Patented Feb. 20, 1917.

Application filed September 18, 1916. Serial No. 120,897. Term of patent 14 years.

To all whom it may concern:

Be it known that I, HAROLD H. BROWN, a citizen of the United States, residing at Indianapolis, in the county of Marion and State of Indiana, have invented a new, original, and ornamental Design for Plates or Similar Articles, of which the following is a specification, reference being had to the accompanying drawings, forming part thereof.

The figure is a plan view of a plate showing my new design.

I claim:

The ornamental design for a plate or similar article as shown.

HAROLD H. BROWN.
